(57) **CLAIM**

The ornamental design for a pair of running shoes, as shown and described.

DESCRIPTION

FIG. 1 is a front, right and top perspective view of a pair of running shoes showing my new design for a right foot;
FIG. 2 is a front, left and bottom perspective view thereof;
FIG. 3 is a rear, right and top perspective view thereof;
FIG. 4 is a front elevational view thereof;
FIG. 5 is a rear elevational view thereof;
FIG. 6 is a left side elevational view thereof;
FIG. 7 is a right side elevational view thereof;
FIG. 8 is a top plan view thereof; and,
FIG. 9 is a bottom plan view thereof.

A pair of running shoes for a left foot is a mirror image of the pair of running shoes for a right foot as shown in FIGS. 1 to 9.

The broken lines and areas within the broken lines form no part of the claimed design.
